UNITED STATES PATENT OFFICE.

COLIN DOUGLAS BARRETT, OF PROVIDENCE, RHODE ISLAND, ASSIGNOR TO FARBER BROTHERS, A COPARTNERSHIP CONSISTING OF LOUIS FARBER AND HARRY FARBER, OF NEW YORK, N. Y.

DESIGN FOR A METAL BORDER STRIP FOR ARTICLES OF HOLLOW SILVERWARE.

Application filed December 2, 1924. Serial No. 11,558. Term of patent 3½ years.

To all whom it may concern:

Be it known that I, COLIN D. BARRETT, a citizen of the United States, and a resident of Providence, in the county of Providence and State of Rhode Island, have invented and produced a certain new, original, and ornamental Design for a Metal Border Strip for Articles of Hollow Silverware, of which the following is a specification, reference being had to the accompanying drawings, forming part thereof.

The figure is a representation of a strip or panel illustrating my new design.

My border strip is a separate article of manufacture intended to be applied to articles of hollow silverware.

I claim:

The ornamental design for a metal border strip for articles of hollow silverware, as shown.

COLIN DOUGLAS BARRETT.
